SMOKING PIPE

Calvin W. Lynch, 611 Wilton Road, Baltimore, Md.

Filed Oct. 26, 1964, Ser. No. 82,323

Term of patent 14 years

(Cl. D85—8)

FIG. 1.

FIG. 4.

FIG. 2.

FIG. 3.

FIG. 5.

FIG. 7

FIG. 6.

FIG. 8.

FIG. 9.

FIG. 10.

FIG. 11.

FIG. 12.

FIG. 14.

FIG. 13.

FIG. 1 is a perspective view of a smoking pipe, embodying my new design;

FIG. 2 is a side elevational view thereof;

FIG. 3 is a bottom plan view thereof;

FIG. 4 is a sectional view thereof taken on the line 4—4 of FIG. 2;

FIG. 5 is a side elevational view of another embodiment of my new design;

FIG. 6 is a plan view thereof;

FIG. 7 is a sectional view thereof taken on the line 7—7 of FIG. 5;

FIG. 8 is a perspective view of another embodiment of my new design;

FIG. 9 is a side elevational view thereof;

FIG. 10 is a bottom plan view thereof;

FIG. 11 is a sectional view thereof taken on the line 11—11 of FIG. 9;

FIG. 12 is a side elevational view of another embodiment of my new design;

FIG. 13 is a top plan view thereof; and

FIG. 14 is a sectional view thereof taken on the line

The dominant features of my design reside in the portions shown in full lines. In each embodiment of the pipe, the sides of the bowl not shown are substantially the same as the sides shown.

I claim:

The ornamental design for a smoking pipe, as shown and described.
